TWO POINT SWITCH MECHANISM
William J. Williams, 8151 N. Ridgeway Ave.,
Wilmette, Ill.
Filed May 16, 1960, Ser. No. 29,546
2 Claims. (Cl. 200—166)

This invention relates to an improved electromechanical device such as a relay, solenoid or the like and especially includes an improved double breaking, switching mechanism therefor.

More specifically, it is an object of this invention to provide a switch lever mechanism suitably mounted for movement to and from two fixed contacts by suitable operating means, said mechanism having two spaced movable switch contacts simultaneously operable in a direction to make the break both said sets of contacts and also in another direction to effect a proper seating of said contacts upon each individual make and break regardless of any variations in position and alignment of the contacts.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawings of a form of the invention, which may be preferred, in which:

FIGURE I is a plan view of the switching device of this invention;

FIGURE II is a section on the line II—II of FIGURE I;

FIGURE III is an elevation taken from the line III—III of FIGURE I;

FIGURE IV is a section taken on the line IV—IV of FIGURE II;

FIGURE V is a section taken on the line V—V of FIGURE IV;

FIGURE VI is an exploded view of the switching device to expose its elements; and

FIGURE VII is a diagram showing the triangular relationship of contacts and pivot.

FIGURE VIII is an elevation, partly in section, showing the switch mechanism as associated with solenoid coils, for operation therewith;

FIGURE IX is an elevation, partly in section and showing the solenoid operated plunger and pin in position for breaking the switch contacts;

FIGURE X is a diagrammatic view showing the wiring connections between the switch and solenoids;

FIGURE XI is a section taken substantially on the line XI—XI of FIGURE VIII; and

FIGURE XII is a partial view showing an alternate wiring arrangement.

Referring to the particular embodiment of the invention illustrated in the drawings in FIGURES I, II and III, there is shown the insulated circular-shaped base 10 which has a central opening 11 therein adapted, in the particular instance illustrated, to receive an operating plunger 12 carried by a mechanism or unit with which the switch is designed to be associated. A pair of fixed contacts 14 and 15 are positioned adjacent the periphery of the disc 10 as shown, provision being illustrated for suitable electrical connections for the leads of said associated unit. The switching mechanism hereof includes a transversely arranged movable lever assembly 18 carrying at one end contacts 19 and 20, contact 19 adapted to co-act with fixed contact 14 and contact 20 with contact 15. More in detail in the particular lever assembly illustrated in this present embodiment of the

2

invention, it will be seen that there is provided a main metal base piece 21, having a curled end 22 forming the pivot for the lever, the other end of the elongated metal strip 21 having a transverse enlargement 24 to which the movable contacts 19 and 20 are insulatedly connected and are arranged to be moved in unison by the lever assembly 18. To this end each of the movable contacts 19 and 20 are connected with a crosspiece 25, which in turn, through spaced insulating plates 26 and 27, is riveted to said cross enlargement 24 by rivets 28, the rivets themselves being insulated by grommets 29, as illustrated. There is also provided a top piece 30 connected to the cross extension 24, said element 30 having an upwardly bent cone-shaped section 31 adapted to center the return coiled spring 32, in the particular embodiment of the invention shown herein.

An important feature of the present invention is the pivoting of the lever 18 to insure correct setting of each of the movable contacts which act in unison, as stated, said pivot being illustrated herein in FIGURES IV, V, and VI. In detail, this pivotal support consists of a bracket 35 fixed to the base 10 by rivets 36 and 37 (see FIGURE VI), said bracket 35 adapted to adjustably support a pivot carrier or housing 40 for the actual pivot at the end of the lever mechanism 18. In the particular embodiment illustrated, this support consists of a U-shaped member 40 having side portions 41 and 42 and an end 43, the end 43 having an elongated opening 44 for cooperation with a tapped opening 45 in the supporting bracket 35 so that the position of the supporting pivot for the lever may be moved toward and away from the base 10 and fixed in a desired position. Thus, a screw 46 is adapted to be threaded into the tapped opening 45 with the end wall 44 of the support 45 located therebetween. A serrated washer 47 is located against the outer face of the upright piece 35 and the U-shaped bracket 40 fits over the upright support 35 with washer 47 therebetween. Then screw 46, first passing through a washer 49 on the outside of the face 43 and underneath the head of the screw 46, extends through elongated opening 44 into tapped hole 45 in support 35. Thus, by loosening the screw 46 the U-shaped pivot support 40 for the lever 18 may be adjusted as desired toward and away from the base 10. Hence, contacts 19 and 20 may be spaced variously as desired relative to the first contacts 14 and 15.

The U-shaped bracket 40, as illustrated more fully in FIGURES IV, V and VI forms a bearing for the pintle 50 around which and spaced therefrom the curved bearing element 22 of the lever 21 is positioned. As heretofore indicated, an important feature of the entire invention is to provide a mechanism which will permit the lever 18 to not only swing in an arc around pintle 50 and move the free end of lever 18 toward and away from the base 10, but also to tilt or rock on the pivot. To this end, as clearly shown in FIGURES IV and V, the curled end bearing 22 is larger than pintle 50 and has a central detent 53 therein, extending through the inside thereof and contacting the pintle 50 as shown. It will also be noted that the curved bearing portion 22 of the lever is spaced as at 54 and 55 from the walls of the U-shaped bracket 40 to permit this tilting and pivoting of the lever with respect to the pintle 50.

To satisfactorily position the spring 32, there is provided an elongated bracket member 56 straddling the lever 18 and riveted as at 57 and 58 to the base 10. This bracket 56 is punched with an opening 60 to form an inner ridge 61, so that the coiled spring 32 is properly centered between the ridge 61 and cone 31 in proper position to contact the lever assembly 18.

Operation of Switch

In FIGURE VII there is shown a diagrammatical illustration of the "three point" effect in the operation of the switch mechanism hereof, where it will be seen that the indentation 53 forms, in effect, at one end a single unitary pivot point A for the lever 18, said lever being illustrated diagrammatically as a triangle in FIGURE VII. At the other end of lever 18, the lines B and C indicate the central axis of the movable switch contacts 19 and 20 which, being fixed to each other, move in unison as stated, supra. If both movable contact points are in perfect alignment with their corresponding fixed contacts, the actuation of the switching mechanism will merely swing lever 18 around the pintle 50 without any tilting or lateral or transverse movement. However, if one of the contacts 14 or 15 is not in proper alignment with the movable corresponding contact, or the lever mechanism 18 is twisted or not substantially level so that the one set of contacts as at B, for example, makes connection before the other one at C has satisfactorily engaged its fixed contact, then the bearing 22, being loose on pintle 50, by reason of the point contact of the indentation 53 in bearing 22 on the pintle 50, will tilt so that lever 18 will also tilt until the other contact as at C properly seats. The three point triangular illustration of FIGURE VII indicates this operation. In the illustrated application of the switching mechanism hereof, the suitably operated plunger 12 moves lever 18 in one direction to open the switch contacts and coiled spring 32 moves it in the opposite direction to close the contacts. As shown, both contacts of each set are curved as illustrated, for example in FIGURE III, as at D (FIGURE VII) to further facilitate the proper aligning action just described.

The foregoing switch mechanism may be used for providing a double break in a single circuit, and I have found the same of special utility in connection with electro-mechanical devices such as relays, solenoids, and the like, and illustrate in FIGURES VIII through XII a double coil solenoid with the internal-external circuits, illustrated, utilizing said switch mechanism.

Referring to FIGURE VIII, it will be seen that the solenoid has a casing 70 on top plate 71, to which the base 10 of the foregoing switch mechanism is secured as illustrated. Moreover, on FIGURE VIII I show the cap 72 for the switch mechanism itself located in place, and have arranged a screw 73 passing through said cap and into screw threads on the protrusion 61 of the element 56 within the switch mechanism.

Within the casing 70 of the solenoid is an outer high resistance continuous duty coil 75 of relatively fine wire. The other coil 76 is located inside the coil 75, coil 76 being a low resistance, high-powered, pull-in coil for temporary connection as will hereinafter appear. These coils are suitably located in the casing as shown, and a typical solenoid armature core or plunger 78 is positioned to be properly moved when the coils are energized, plunger 78 contacting the switch pin or plunger 12, as will hereinafter appear.

The solenoid is arranged to do substantial mechanical work and hence a much heavier flux field is required at the beginning of its stroke than is necessary to hold the core 78 in upper position after the stroke has been completed. To effect this result, I have provided a construction so arranged that both coils 75 and 76 operate at the initial or break-away action of the solenoid, whereupon subsequently the pull-in winding or winding 76 is automatically disconnected by the switch mechanism.

Referring to FIGURE X, the internal and external circuits are here illustrated. The external circuit has an input lead 80 which may be controlled, if desired, by suitable outside or remote control manual or automatic switch 81, said input lead 80 being connected with solenoid switch terminal 82 which also carries one of the double switch contacts 14, as illustrated in FIGURE III.

From the connection point 83 of said input terminal 82 a lead 84 connects to terminal 85, whence the high resistance, low-powered continuous duty coil 75 is connected, the other terminal section 87 of coil 75 being connected to contact 88 as shown, hence lead 89 joins the same to outlet terminal 90 for the external circuit to which the external circuit outlet lead 91 is connected.

The coil 76 for producing the heavy flux field at the initiation of the operation of the solenoid is located within coil 76 as shown, and consists of a plurality of a large number of turns of low resistance relatively coarse wire. The circuit therefor is illustrated in FIGURE X, where it will be seen that from the input terminal 82 the current passes to contacts 14 and 19 of switch bridge 25, hence through contacts 20 and 15 to connector 94. Then a lead 95 is connected to a terminal 96 which, in turn, has a lead 97 connected to the input terminal of the inner coil 76. The output circuit for said coil 76 includes a lead 99 connected to a contact 100, which by lead 101 is connected to the outlet terminal 90 as shown. As shown in FIGURE XII a suitable ground 102 may be substituted for the return wire 91.

Operation

From the foregoing it will be seen that, when switch 81 is closed, energy will be supplied to both coils 75 and 76. At the start or "dead" position the core or plunger 78 is at the lowermost position and plunger 12 will be removed from contact with the switch arm 21, since spring 32 has closed the switch contacts 14 and 19, as well as 20 and 15. Both circuits for the two coils 75 and 76 are parallel, as shown, and upon initial energization both coils work conjointly to produce the heavy field flux and permit the plunger 78 to effect the work required. As the plunger 78 moves upwardly, as shown in FIGURE VIII, core 78 will act on the plunger 12 which will contact the switch lever, as shown in FIGURE IX, and simultaneously open both points 14 and 19 and 20 and 15. This disconnects only the high powered coil 76 and leaves the continuously operating lower powered coil 75 in circuit until external switch 81 is finally broken. The coil 75 has sufficient power to hold the plunger in the position illustrated with the switch contacts 14 and 19, as well as 20 and 15 open, while switch 81 is closed. When switch 81 is finally opened both coils 75 and 76 become deenergized and the parts return to initial or "dead" position.

An important feature of my solenoid construction involves the use of my accurately operating double breaking switch mechanism hereof, since the life of the unit as a whole has been greatly increased by this switch, due to certain electrical phenomena involved in breaking the circuit in two places instead of one, especially when using direct current.

In FIGURE XII, I show a modification in which one of the external leads 91 is grounded, in case the mechanism be used in a "grounded" system.

It is apparent that, within the scope of the invention, modifications and different arrangements may be made other than is herein disclosed, and the present disclosure is illustrative merely, the invention comprehending all variations thereof.

What I claim is:

1. A substantially three-point electrical switching mechanism including a lever portion; a base portion carrying thereon a first pair of electrical contacts and providing thereon a pintle for pivotal support of said lever; a second pair of spaced contacts carried on one end of said lever portion to engage said first pair of contacts; pivot means adjacent the other end of said lever portion including a curved end bearing carrying therein a transverse indentation for forming a substantially point pivot for said lever on the pintle of said base portion wherein said pivot means and said second pair of contacts define three points in a plane for accurately positioning said second pair of contacts on said first pair of contacts; a biasing means

operating normal to said plane and in one direction against said lever portion to rotate said lever portion about said point pivot and to close said second pair of contacts against said first pair of contacts; and selectively operative means operating normal to said plane and against said lever portion in the opposite direction to move said lever portion about said point pivot to disengage said second pair of contacts from said first pair of contacts.

2. In an electric switch including a lever portion; an insulating base portion having a central opening therein to receive a remotely operative force member, a first pair of contacts on said base on one side of said opening, and a pintle for providing a pivotal support on the other side of said opening for receiving said lever portion; a second pair of contacts carried on one end of said lever to engage said first pair of contacts; pivot means adjacent the other end of said lever including a curved end bearing carrying therein a transverse indentation forming a substantially point pivot on the pintle of said base portion, whereby said pivot means and said second pair of contacts define three points in a plane forming means for accurately seating said second pair of movable contacts on said first pair of movable contacts; biasing means operating normal to said plane and against said lever portion to rotate said lever portion about said point pivot for engaging said second pair of contacts with said first pair

of contacts; and a mechanical member projecting through the opening in said insulating base and operating normal to said plane against said lever portion in the opposite direction to rotate said lever portion about said point pivot for disengaging said second pair of contacts from said first pair of contacts, whereby said second pair of contacts are always leveled into engagement with said first pair of contacts upon withdrawal of said mechanical force member from said lever portion and by operation of said biasing means against said lever portion.
